UNITED STATES PATENT OFFICE.

JAMES W. BUNN, OF HENRY, TENNESSEE.

RAIL-TIE.

1,264,008.

Specification of Letters Patent. Patented Apr. 23, 1918.

Application filed November 4, 1916. Serial No. 129,483.

To all whom it may concern:

Be it known that I, JAMES W. BUNN, a citizen of the United States, residing at Henry, in the county of Henry and State of Tennessee, have invented certain new and useful Improvements in Rail-Ties; and I do hereby declare the following to be a full, clear, and exact description of the invention, such as will enable others skilled in the art 10 to which it appertains to make and use the same.

The object of this invention is the provision of a metallic rail tie formed of a plurality of detachably connected sections, the 15 said sections having rail seats thereon and certain of the sections having rail base clamping elements formed integral therewith, the rail sections and the rail flange engaging elements being of such construction 20 as to admit of the rails of a track being conveniently and expeditiously mounted on the tie and clamped in operative position.

Other objects will appear and be better understood from that embodiment of my invention of which the following is a specification, reference being had to the accompanying drawing forming a part thereof, in which:

Figure 1 is a top plan view of a rail tie, 30 showing the manner of clamping the rail sections thereon,

Fig. 2 is a side elevation of the tie with the rail in section,

Fig. 3 is a perspective view of one end of 35 the tie, showing the tie sections separated and in the position they assume when the rails of the track are being mounted thereon.

Referring to the drawing in detail, the numerals 1 and 2 designate a pair of tie sections, which are identical in form and construction, and the numeral 3 represents an intermediate section positioned between the sections 1 and 2. The sections 1, 2 and 3 when assembled coöperate to form a tie 40 structure. Each of the sections 1 and 2 is provided, at its lower edge with an outwardly extending flange 4, the said flanges 4 on the sections 1 and 2 serving to provide a relatively wide supporting base for the tie 45 structure. The tie sections 1, 2 and 3 are provided, at spaced points, with slotted openings 5, which receive bolts 6, one end of each bolt being threaded and having a nut thereon that is adjustable against the adjacent 50 rail tie section. The plates 1, 2 and 3 are each provided adjacent their opposite ends

with rail seats 8. The rail seats are formed by cutting out portions of the upper edges of the sections 1, 2 and 3, and the cutout portions are located at such points on the 60 respective sections that the side walls of the cutout portions in the adjacent sections lie in echelon formation, shown more particularly in Figs. 1 and 3 of the drawing. One side wall of each cutout portion in the sections 1 and 2 is provided with a lateral extension 9, which is formed integral with the mentioned side wall of the section, and the said extensions overlie the adjacent cutout portions and have their upper surfaces lying 70 flush with the upper edges of the respective sections. Each of the sections 1 and 2 has the extension 9, at one end, formed on the outer side wall of the adjacent cutout portion and the extension at the opposite end 75 formed on the inner side wall of the adjacent cutout portion, and each of the outer sections 1 and 2 has the cutout portion with the extension formed on the outer side wall thereof alining with the adjacent cutout portion in the intermediate section 3, and with that cutout portion in the other outer section that has the extension 9 formed on the inner side walls, as shown in Figs. 1 and 3 of the drawing. The widths of the lower ends of 80 the cutout portions in the sections 1 and 2 greatly exceed the width of the cutout portions 8 in the intermediate section 3.

In positioning the rails on the tie, the sections, forming the tie, are separated, as 90 shown in Fig. 3 of the drawing, and the base flanges are then extended through the cutout portions in the intermediate section and through the cutout portions in the outer sections 1 and 2, the outer sections 1 and 2 95 being so positioned with relation to each other, that the base flanges of the rails will engage those walls of the cutout portions in the sections 1 and 2 that are opposite the walls that have the extensions 9 formed 100 thereon, as shown in dotted lines in Fig. 3. When the rails have thus been positioned, the sections 1 and 2 are moved relatively of 105 each other, so as to cause the extensions 9 to engage over the adjacent sides of the base flanges so as to hold the rails in position, and the sections 1 and 2 are then moved in the direction of and in contact with the intermediate section 3. It will, therefore, be seen, that the extensions 9 serve as rail 110 clamping means. After the extensions 9 have been engaged over the base flanges of

the rails, the fastening bolts 6 are extended through the openings 5, in the sections 1, 2 and 3, so as to connect the sections and the nuts 7 are then turned on the bolts and adjusted against the adjacent outer section, so as to hold the bolts against accidental removal.

Having thus described my invention what I claim as new, is:

10 A rail tie comprising a pair of movable outer sections, a relatively stationary intermediate section, the lower end of each outer section bent laterally in opposite directions to provide a supporting flange, each of said 15 sections provided with registering openings

when the outer sections are moved into rail engaging position, said sections each having their upper sides cut out to provide a rail seat, and means adapted to extend through the openings of the sections to hold the sections against relative movement with relation to each other when in rail engaging position. 20

In testimony whereof I affix my signature in presence of two witnesses.

JAMES W. BUNN.

Witnesses:

J. W. ROSEBERRY,
T. N. FAUST.
